UNITED STATES PATENT OFFICE.

WILLIAM C. STEVENS, OF SUMMIT, NEW JERSEY, ASSIGNOR TO THE CUTLER-HAMMER MFG. CO., OF MILWAUKEE, WISCONSIN, A CORPORATION OF WISCONSIN.

ELECTRIC SWITCH.

1,269,655.

Specification of Letters Patent. Patented June 18, 1918.

Application filed April 4, 1916. Serial No. 88,864.

To all whom it may concern:

Be it known that I, WILLIAM C. STEVENS, a citizen of the United States, residing at Summit, in the county of Union and State of New Jersey, have invented new and useful Improvements in Electric Switches, of which the following is a full, clear, concise, and exact description, reference being had to the accompanying drawing, forming a part of this specification.

This invention relates to improvements in electromagnetic switches for motor control and other purposes and more particularly to that type of switch wherein a single coil serves to actuate the same and also to restrain its operation during excessive current conditions.

The invention has among its objects to provide a switch of the aforesaid type which will be more positive and reliable in operation and susceptible of a wider range of adjustment than those heretofore proposed.

A further object is to provide such a switch wherein adjustment may be obtained without affecting the magnetic circuits thereof.

Other objects and advantages of the invention will hereinafter appear.

The invention will now be more specifically described in connection with the accompanying drawing which illustrates one of the various possible embodiments thereof.

In the drawing,

Figure 1 is a front elevation of the switch, and,

Fig. 2 is a side elevation thereof partly in section.

The switch includes coöperating contacts 1 and 2, the former being fixed to a support 3 upon a panel 4 and the latter being yieldingly mounted in a conventional manner upon a movable arm 5. The arm 5 is mounted upon a pivot pin 6 carried by and between extensions 7 of non-magnetic bracket 8 fixed to the panel 4. The arm 5 is bifurcated or longitudinally slotted, to straddle the bracket 8 and receive a second arm 9 also pivotally mounted upon the pin 6. These two arms form armatures for an electromagnetic winding 10, and said arms are so designed that the mechanical inertia of the former will materially exceed that of the latter.

The winding 10 is mounted upon a magnetic core 11 fixed to a magnetic plate 12

mounted on panel 4. The core 11 is positioned to aline with the upper end of the arm 9 while plate 12 has an extension 13 paralleling the core to aline with the upper end of arm 5. The core 11 and extension 13 thus form holes for the arms 9 and 5 respectively and said arms are respectively provided with non-magnetic plates 14 and 15 to prevent sticking thereof to said poles.

Both arms 5 and 9 have rearward extensions, the former having a slotted extension 5^a and the latter an extension 9^a fitting within the former. Extension 5^a carries a cross bar 17 forming a stop for extension 9^a and said cross bar has an adjustable stop screw 18 to engage bracket 8, said extension 5^a being bifurcated to straddle said screw. The arm 9, including its extension, is of magnetic material but the arm 5 is of magnetic material only from its upper extremity to the point X, the remainder of said arm including the entire extension 5^a, being of non-magnetic material. However, the non-magnetic extension 5^a is provided at its rear end with a magnetic block 19 in line with the end of magnetic plate 12 which projects downwardly through bracket 8. The front face of this block is in close proximity to the end of the extension 9^a of arm 9 and is curved concentrically with the arc in which the end of said extension moves to thereby maintain a fixed air gap between said parts throughout the movement of the former.

Thus it will be observed that upon energization of the electromagnetic winding 10 the magnetic flux thereof will be divided between the two paths indicated in broken and dotted lines. The flux taking the broken line path obviously tends to attract the arm 5 to close the switch, while that taking the dotted line path tends to attract the arm 9. Further, it will be observed that the flux taking the dotted line path, in passing through the magnetic block 19 attached to the extension of arm 5 on its way to the extension of arm 9, also serves to attract or hold said block with the result of opposing the attraction of arm 5 by the flux taking the broken line path. Moreover, in view of the relation of the block 19 and extension 9^a of arm 9, said arm may move to attracted position without varying the attractive force exerted on the block 19 and hence the force in opposition to the closure of arm 5.

The arm 9, however, is connected to the

extension of arm 5 through a tension spring 20. This spring is connected at one end to a lug 21 on the magnetic block 18 and is connected at its opposite end by an adjustable device 22 to a lug 23 on the extension of arm 9. Hence it will be observed that when the arm 9 is attracted it will tension the spring 20 thereby offsetting or compensating for the mechanical inertia of the arm 5 to the extent of the energy stored in said spring. In other words, the arm 9 upon attraction increases the sensitiveness of the arm 5 to attraction by the magnet through the medium of spring 20.

15 Thus, considering the switch in its entirety, the winding 10 when energized will exert opposing pulls on arm 5 and a unidirectional pull on arm 9. The pull on arm 9 is opposed only by the relatively slight mechanical inertia thereof and the minimized opposing force of spring 20, while the magnetic opposing pull on arm 5 is supplemented by the relatively great mechanical inertia of said arm. Arm 9 will accordingly respond prior to arm 5 and in approaching pole 11 reduces the reluctance of the path of that flux acting to attract the same and to oppose attraction of arm 5. This insures a strong opposing pull on arm 5 but at the same time effects a change in the relative reluctances of the two magnetic circuits whereby a decrease in current will effect a greater reduction in the flux of the dotted line circuit than in the flux of the broken line circuit. Moreover, the attraction of arm 9 tensions the spring 20 to supplement the closing pull exerted on arm 5 whereby at some critical current value the combined magnetic and mechanical forces exerted on arm 5 will necessarily preponderate the combined magnetic and mechanical opposing forces to close the switch. On the other hand, the construction described insures a time element in the closure of the switch whereby if the winding is initially subjected to a current rising above said critical value the preponderation of the two opposing forces will necessarily be reversed with the result of maintaining the switch in open position until the current falls to said critical value.

If desired, the arm 5 may be designed to have such mechanical inertia as to positively insure against its attraction without the assistance of spring 20 or any of the well known means may be provided to retard the building up of the flux of the broken line circuit upon initial energization of winding 10. Such means will positively insure an opportunity for action of the other means to control the switch as described. Moreover, with the construction described, the sensitiveness of the arm 5 for attraction by winding 10, and hence the critical current value, may be varied through a wide range

by mechanical and magnetic adjustments. The mechanical adjustment is afforded by the adjustable device 22 associated with the tension spring, which device enables variation of the degree of tension of spring 20 effected by attraction of arm 9. This, in turn, varies the degree of supplementation of the closing pull of magnet 10 and without in any wise affecting the normal positioning of the arm 5 or, in other words, without in any wise affecting either magnetic circuit. On the other hand, the magnetic adjustment is provided for by the adjustable stop screw 18 on the extension of arm 5, which provides for variation of the air gap between the lower extremity of the magnet frame and the magnetic block 19 on arm 5, and proportional variation in the air gap between the arm 5 and pole 13. This in turn effects a variation in the relative reluctances of the two magnetic circuits with a consequent variation in the effect of rising and falling currents upon the fluxes of the two circuits. Obviously, therefore, these adjustments individually and jointly provide for adaptation of the switch to widely varying conditions.

It will, of course, be understood that when the switch closes the arm 5 approaches poles 13 and 11 of the magnet to reduce the reluctance of the broken line magnetic circuit and at the same time separates the block 19 from the lower end of the magnetic frame to increase the air gap in the dotted line magnetic circuit which insures a strong holding pull on arm 5 and further insures against subsequent predominance of the opposing fluxes.

What I claim as new and desire to secure by Letters Patent is:

1. In an electromagnetic switch, in combination, coöperating switch contacts, an actuating member for one of said contacts, electromagnetic means subjecting said member to opposing pulls variable relatively by variations in the current supplied to said means and means adjustable to vary the sensitiveness of response of said member for actuation of said contact while maintaining a given relative adjustment of the opposing pulls of the said electromagnetic means.

2. In an electromagnetic switch, in combination, coöperating switch contacts, an actuating member for one of said contacts, electromagnetic means subjecting said member to opposing pulls variable relatively by variations in the current supplied to said means, means to effect relative adjustment of such pulls for response of said member at any one of a number of critical current values and means adjustable to vary the sensitiveness of response of said member while maintaining a given relative adjustment of the opposing pulls of said electromagnetic means.

3. In an electromagnetic switch, in combination, coöperating contacts, an actuating member for one of said contacts, an electromagnetic operating winding for said member having magnetic circuits whereby its magnetic flux exerts opposing pulls on said member and means subjected to a uni-directional pull by said winding and responsive to vary the sensitiveness of response of said member.
4. In an electromagnetic switch, in combination, coöperating contacts, an actuating member for one of said contacts, an electromagnetic operating winding for said member having magnetic circuits whereby its magnetic flux exerts opposing pulls on said member and means subjected to a uni-directional pull by said winding and responsive prior to said member to supplement the magnetic pull on said member in a single direction.
5. In an electromagnetic switch, in combination, coöperating contacts, an actuating member for one of said contacts, an electromagnetic operating winding for said member having magnetic circuits whereby its magnetic flux exerts opposing pulls on said member and means subjected to a uni-directional pull by said winding and responsive prior to said member to mechanically supplement the magnetic pull on said member in a single direction.
6. In an electromagnetic switch, in combination, coöperating contacts, an actuating member for one of said contacts, an electromagnetic operating winding for said member having magnetic circuits whereby its magnetic flux exerts opposing pulls on said member and means subjected to a uni-directional pull by said winding and responsive prior to said member to supplement the magnetic pull on said member in a single direction, said means being adjustable to vary the degree of supplementation of the pull on said member.
7. In an electromagnetic switch, in combination, coöperating contacts, an actuating member for one of said contacts, an operating winding for said member having magnetic circuits whereby its magnetic flux exerts opposing pulls on said member and means responsive to said winding independently of said member to vary the reluctance of the magnetic circuit, the flux of which opposes actuation of said member.
8. In an electromagnetic switch, in combination, coöperating contacts, an actuating member for one of said contacts, an operating winding for said member having magnetic circuits whereby its magnetic flux exerts opposing pulls on said member and means responsive to said winding independently of said member to vary the reluctance of the magnetic circuit, the flux of which opposes actuation of said member, said means upon attraction also acting to supplement the reverse pull on said member.
9. In an electromagnetic switch, in combination, coöperating contacts, an actuating member for one of said contacts, an operating winding for said member having magnetic circuits whereby its magnetic flux exerts opposing pulls on said member and means subjected to a uni-directional pull by said winding and adapted upon response to vary the reluctance of one of said magnetic circuits with respect to the other and further to mechanically supplement the actuating force exerted on said member.
10. In an electromagnetic switch, in combination, coöperating contacts, an actuating member for one of said contacts, an operating winding for said member having magnetic circuits whereby its magnetic flux exerts opposing pulls on said member, said member having means to adjust the same for relative reluctance variation of said magnetic circuits, and means subjected to a uni-directional pull by said winding and responsive thereto to supplement the actuating pull on said member, said means including adjustable means for varying the degree of such supplementation.
11. In an electromagnetic switch, in combination, coöperating contacts, an actuating member for one of said contacts, an operating winding for said member having magnetic circuits whereby its magnetic flux exerts opposing pulls on said member, said member having means for adjusting the same to vary relatively the normal reluctances of said magnetic circuits, means subjected to a uni-directional pull by said winding and adapted upon response to reduce the reluctance of one of said magnetic circuits and means controlled by said former means to supplement the actuating pull on said member, said last mentioned means being adjustable to vary the degree of such supplementation.
12. In an electromagnetic switch, in combination, coöperating contacts, an electromagnetic winding and separately and progressively responding armature members for said winding, the member last to respond being operatively connected to one of said contacts for actuation thereof and said winding having a magnetic circuit including both of said members, such circuit subjecting said contact actuating member to a restraining pull and being subjected to a reduction of its reluctance upon response of the other of said members.
13. In an electromagnetic switch, in combination, coöperating contacts, an electromagnet having separately and progressively responding armature members, the member last to respond being operatively connected to one of said contacts for actuation thereof, said electromagnet having a magnetic

4 circuit including both of said members, such circuit subjecting said contact actuating member to a restraining pull and being subjected to a reduction in its reluctance upon response of the other of said members and an energy storing connection between said armature members acting to supplement the

actuating pull of said contact actuating member following the attraction of the other of said members.

10

5 In witness whereof, I have hereunto subscribed my name.
